United States Patent Office

Des. 186,670
Patented Nov. 17, 1959

186,670

LOUDSPEAKER

Howard M. Durbin, South Bend, Ind.

Application March 13, 1959, Serial No. 54,990

Term of patent 14 years

(Cl. D26—14)

FIG. 1

FIG. 2

FIG. 3

FIG. 4

Fig. 1 is a rear elevational view of a loudspeaker, showing my new design;

Fig. 2 is a side elevational view, the opposite side being substantially a mirror image thereof;

Fig. 3 is a front elevational view; and

Fig. 4 is a cross-sectional view thereof, taken along line 4-4 in Fig. 3.

I claim:

The ornamental design for a loudspeaker, as shown and described.
